REPTILE SIMULATING ILLUSION TOY

John A. Frampton, Columbus, Ohio

Application June 22, 1951, Serial No. 232,961

1 Claim. (Cl. 272—27)

1

This invention relates to a novelty toy and has for its primary object to afford amusement and entertainment.

Another object is to move a portion of a simulated reptile or the like when a movable element of a container is actuated and thus to create the illusion that the container houses a live reptile or the like.

The above and other objects may be attained by employing this invention which embodies among its features a box or the like having a hinged cover, a false bottom in the box, a body of flexible material in the box simulating in shape and coloring a reptile or the like and means within the box connected to the body and to the cover and operating beneath the false bottom for flexing a portion of the body as the cover moves to open position.

Other features include a crank arm pivotally carried by the under side of the false bottom and extending therethrough into the body, yielding means connected to the crank arm and to the false bottom for holding the body extended, and a flexible member connected to the crank arm and to the box cover for moving the crank arm against the effort of the yielding means and flexing the body to simulate life therein.

In the drawings:

Figure 1 is a plan view of an embodiment of this invention showing portions broken away more clearly to illustrate the details of the toy;

Figure 2 is a longitudinal sectional view taken substantially along the line 2—2 of Figure 1;

Figure 3 is a transverse sectional view taken substantially on the line 3—3 of Figure 2;

Figure 4 is a horizontal sectional view taken substantially along the line 4—4 of Figure 2;

Figure 5 is a plan view of the device showing the box cover open and the body therein flexed;

Figure 6 is a transverse sectional view taken substantially along the line 6—6 of Figure 5;

Figure 7 is a transverse sectional view taken substantially along the line 7—7 of Figure 5, and

Figure 8 is a perspective view of the false bottom of the box.

Referring to the drawings in detail a box 10 which preferably comprises an elongated hollow body, carries along one longitudinal side edge a cover 12. The hollow body of the present disclosure comprises a bottom 14 having spaced parallel upwardly extending side walls 16 and end walls 18.

Supported within the box 10 intermediate the bottom 14 and cover 12 is an elongated rectangular false bottom 20 having along its longitudi-

2

nal side edges downturned side flanges 22 and along its end edges downturned end flanges 24 and 26. These side and end flanges are adapted to engage the bottom 14 of the box 10 and hold the false bottom 20 in properly spaced relation thereto.

A reinforcing pad 28 is carried on the side of the false bottom 20 near the end thereof adjacent the flange 26 and the false bottom 20 and pad 28 are formed with aligned openings through which extends the pivot portion 30 of a crank designated generally 32. Carried at the upper end of the pivot portion 30 of the crank 32 and projecting perpendicularly thereto is an arm 34 which is received in the body of flexible material to be hereinafter described, to cause said body to flex when the crank 32 is oscillated. An actuating arm 36 is carried by the pivot portion 30 on the under side of the false bottom 20 and lies directly beneath and in spaced parallel relation to the arm 34. An eye 38 is carried by the actuating arm 36 at the end thereof remote from the pivot portion 30 and connected to the eye 38 and to a staple 40 carried by the end wall 36 is an elastic extensible member 42 which is so tensioned as to yieldingly hold the arms 34 and 36 substantially parallel with the side flanges 22.

Formed in the false bottom 20 adjacent the end flange 24 is an opening through which projects an eyelet 44, and coupled to the eye 38 and leading through the eyelet 44 is a flexible member 46. A limiting strap 48 is connected at one end to the cover 12 and at its opposite end to the false bottom 20 and secured to cover 12 adjacent and beneath the limiting strap in any suitable manner is the end of the flexible member 46 remote from the eye 38. It will thus be seen that when the cover is moved to open position, it will exert pull on the flexible member 46 and cause the crank member 32 to move against the effort of the flexible extensible member 42.

A body 50 of flexible material shaped and colored to simulate a reptile is carried by the top side of the false bottom 20 with a portion thereof impaled on the arm 34 and another portion remote from the crank 32 cemented or otherwise attached to the false bottom. In its present embodiment the body 50 is shaped and colored to represent a snake and with the portion immediately adjacent the head impaled on the arm 34 and the tail portion secured to the false bottom 20 it will be evident that upon exerting pull on the flexible member 46, the head portion of the

body 50 will move sideways against the effort of the yielding means 42. With the false bottom 20 mounted in the box 10 as shown and the limiting strap 48 coupled to the box cover 12, it will be evident that as the box cover 12 moves to open position the flexible member will move the crank 32 and cause the body 50 to flex in a lifelike manner.

What is claimed is:

In a toy of the type comprising a box having 10 an open top and a hinged cover for closing the open top of the box, means within the box for surprising one opening the cover thereof comprising a false bottom in said box, a body of flexible material simulating in shape and color a 15 reptile, the rearward portion of said body being fixed atop the false bottom, a crank member pivotally mounted in and extending through the false bottom, said crank member extending into the forward portion of the body for flexing said 20

body, means connected to the crank member and to the cover for moving the crank member as the cover is opened and flexing the body, and yielding means connected to the crank member and to the false bottom for restoring the parts to their initial position as the cover is closed.
